UNITED STATES PATENT OFFICE.

SAMUEL LAWTON, OF BURLINGTON, VERMONT.

BLANKET-MEASURE.

1,281,178.

Specification of Letters Patent.

Patented Oct. 8, 1918.

Application filed August 23, 1917. Serial No. 187,852.

To all whom it may concern:

Be it known that I, SAMUEL LAWTON, a citizen of the United States, residing at Burlington, in the county of Chittenden and 5 State of Vermont, have invented certain new and useful Improvements in Blanket-Measures, of which the following is a specification.

This invention relates to measuring devices and more particularly to a measuring attachment for weaving machines or looms.

The invention has for its principal object to provide a measuring device that will indicate certain predetermined lengths of woven 15 material as it passes from the loom so that the proper length of the woven material may be indicated on the material for facilitating accurate cutting of uniform lengths.

A further object of the invention is to provide 20 a measuring device that will be especially useful in properly measuring blankets woven on a loom and indicating thereon the point at which the border blanket is to be woven so that all of the blanket in a length 25 of material will be of proper length and the borders will be properly positioned.

A further object of this invention is the provision of a blanket measure which consists of comparatively few parts and is simple 30 in construction, but durable and well adapted to withstand the rough usage to which devices of this character are ordinarily subjected.

For a full description of the invention and 35 the advantages and merits thereof, reference is to be had to the following description and the accompanying drawings, wherein is illustrated the preferred form of my invention, in which;

40 Figure 1 is a fragmentary front elevation of a weaving machine or loom showing the attachment applied thereto.

Fig. 2 is a section under line 2—2 of Fig. 1.

Referring to the drawing by numerals, the 45 frame designated generally at A is a part of the ordinary loom or weaving machine and includes the shelf B and supporting standard C at the front of the machine and in front of which the operator or loom tender 50 stands when the machine is in operation. A take up roller at D is mounted on the frame and as indicated at Fig. 1 of the drawings, the end of the roller is journaled in the upright C and as indicated by dotted lines, the 55 woven material passes over the shelf B and around the roller D.

The roller journal carries a sprocket 1 over which a chain 2 is passed. Mounted upon the frame is a bracket 3 which includes the upright 4 projecting vertically above the shelf B and carrying a stud 5. A pulley wheel 6 is mounted upon the stud 5 and is adapted to freely rotate upon the same. This pulley 6 has side flanges which form an annular groove for the reception of the chain 2. The chain also passes around take-up pulleys 7 and 8, shown to advantage in Fig. 2 of the drawing. Each of these take-up pulleys is mounted upon a stud 9 carried by the upright standard C, the latter being provided 60 with convenient slots 12 for the reception of the stud 9 in each pulley. The end of each stud is provided with a fastening nut for the purpose of holding the stud in adjusted position in the slot 12. In this manner the pulleys 7 and 8 may be adjusted with respect to each other for the purpose of taking up slack in the chain or for increasing or decreasing 65 the length of the same.

The ordinary blanket woven on looms of 80 this character measures 103 inches in length and, therefore, a sufficient number of links will be provided in the chain 2 to form a chain of a length equal to the length of the ordinary blanket. The chain, therefore, will 85 have made a complete passage around the pulleys and sprocket as each blanket-length passes over the shelf from the weaving machine.

When a border for the blanket or different 90 color material is to be provided in the blanket it is necessary to stop the machine while the operator makes the necessary adjustments for changing the "filling" to the desired color for indicating the border. For 95 this purpose I have marked certain of the links in the chain by making them of a different color from the other links, for instance red. This will indicate to the operator the place at which the machine is to stop 100 for the purpose of changing "filling" to insert the border in the blanket. Attached to the stud 5 is a finger 13 which is bent to project over the pulley 6 above the immediate center thereof, and this finger will indicate 105 the place at which the machine is to stop; the operator continually watching for the red link to appear beneath the finger whereupon it will be necessary to place the border in the blanket. Since the border usually 110 consists of material of a different color in the form of two or more lines across the

blanket, I have provided two links in red indicated at 10 and these may be relatively closed together and any desired number may be provided.

5 When a blanket of longer length is to be woven a chain with a greater number of links will be mounted on the device, the rollers 7 and 8 being adjusted to take up any slack that might occur. For a shorter blanket the links of the chain will be decreased in number and the rollers 7 and 8 adjusted accordingly.

10 From the foregoing it will be observed that a very simple and durable blanket measure has been provided, and the details of which embody the preferred form. I desire it to be understood, however, that slight changes in the minor details of construction may be made without departing from the 15 spirit of the invention or the scope of the claims hereunto appended.

20 What I claim is:—

25 1. In a measuring device for looms, the combination with a frame and a roller mounted thereon, a flexible chain, means carried by the roller and engageable with the chain to impart motion to the chain when the roller is actuated, means rotatably mounted on the frame and receiving a portion of the 30 chain to expose the latter in view of the operator, and rollers adjustably mounted on the frame and engageable with the said chain and adapted for relative movement toward and away from each other to tighten 35 or slacken the said chain.

2. In a measuring device for looms, the combination with a frame having a roller

40 mounted thereon, and a bracket fixed to the frame, a grooved pulley mounted on the bracket, a flexible chain passing over the said pulley and through the groove and engageable with the said roller for imparting motion to the pulley when the roller is actuated, stud shafts adjustably mounted in the frame and each carrying a pulley, the said 45 chain being looped and passed around the pulleys whereby adjustment of the said studs in the slots may be made to tighten or slacken the said chain.

3. In a measuring attachment for looms, 50 the combination with a frame including a bracket and a roller rotatably mounted on the frame, the roller carrying a sprocket, a flexible chain of a predetermined length passing over the said sprocket, means mounted 55 upon the bracket and receiving said chain to support a portion of the latter above the said frame, the said chain having certain indicia thereon adapted to be exposed to view above the frame when passing over the said means, a finger attached to the bracket and overlying the exposed portion of the said chain above the frame, and adjustable means mounted on the frame and engageable with the chain to permit tightening and loosening 60 of the said chain when the length thereof is varied.

65 In testimony whereof I affix my signature in presence of two witnesses.

SAMUEL LAWTON.
